UNITED STATES PATENT OFFICE.

CHARLES G. SHAFFER, OF PATERSON, AND GEORGE TREFS, OF MONTVILLE, NEW JERSEY.

CONTROL MEANS FOR MOLD-MAKING MACHINES.

1,379,421.

Specification of Letters Patent. Patented May 24, 1921.

Application filed January 14, 1921. Serial No. 437,344.

To all whom it may concern:

Be it known that we, CHARLES G. SHAFFER and GEORGE TREFS, citizens of the United States, residing at Paterson and Montville, respectively, in the counties of Passaic and Morris, respectively, and State of New Jersey, have invented certain new and useful Improvements in Control Means for Mold-Making Machines, of which the following is 10 a specification.

This invention relates to apparatus for making molds and particularly to that class of such apparatus in which the operations of compacting the sand or other mold material in the flask and withdrawing the mold from the pattern after forming are an incident of the flow of a fluid, as air, steam or electricity. For example, in machines using air as the power medium the main table or 15 head of the machine is the movable element of a cylinder-and-piston arrangement, being capable of being reciprocated by air to cause "bumping" and consequent settling of the mold material in the flask or of movement plunger-fashion by air to force the mold material against a ramming head and thus "squeeze" the mold material into compact state, and it in turn forms the relatively fixed element of another piston-and-cylinder arrangement the movable part of which is movable by air to raise or strip the mold, after the compacting of the mold material has thus been accomplished, from the pattern, which remains in fixed relation to 20 said main table or head. The operation of such machines as at present constructed is entirely subject to the will of the attendant, in consequence of which the product varies greatly in quality, the mold being either 25 over- or under-compacted, and much time is wasted except in those extraordinary cases where special skill and care are devoted to the work. Thus, in an air-operated machine, since the control of the air is manual, 30 the attendant can cause the material to be "bumped" or "squeezed" not enough or too much for the good of the product and he can waste time in the over-doing of either 35 of these operations and also when, having 40 raised or stripped the mold from the pattern, he removes the mold, lowers the flask-frame, places a fresh flask on the latter and fills it with the mold material. These difficulties are a source of constant annoyance 45 and great expense in all molding shops using 50 molding machines; and it is the object,

therefore, of this invention to provide a control means for such a machine whereby its operations will be quite beyond the control of the attendant and fixed to occur at regular or constant time intervals, so that the product will be standardized and waste of time avoided.

In the accompanying drawings, Figure 1 shows a mold making machine 65 provided with our control means;

Fig. 2 is a plan of said control means; Figs. 3 and 4 are elevations of the cams thereof; and

Fig. 5 shows in side elevation the braking 70 regulator of said control means.

The drawings show a mold making machine of the air-operated type. *a* is its cylinder-base and *b* is its main table or head secured at the top of the main piston *c* arranged within said cylinder-base. The machine may be either of the type adapted to "bump" the sand or other material in the flask in order to settle it or of the type wherein the filled flask is moved toward a 75 ramming head in order to compress the material; the present machine is one of the first type and to this end its cylinder *a* has a fluid exhaust port *a'* near its lower end. Above the head *b* are the open frames *d* and *e* (the latter surrounding the former) for respectively supporting the platen or pattern plate *f* and the flask *g*; these are supported above head *b* by uprights *h* and *i* extending upwardly from said head. The 80 flask has dowels *g'* which enter suitable holes in the frame *e* for centering it with reference thereto. The piston *c* affords at *j* a cylinder for the secondary piston *k* whose upper portion is a plate *k'* which by means of uprights *l* supports the flask-raising frame *m* which surrounds the frame *e*. *n* indicates a fluid supply source (here, air under pressure) and *o* and *p* conductors for the fluid leading from said source respectively to cylinder *a*, at its lower end, and to the interior of a chamber *c'* in piston *c*, here shown as containing a sluggish liquid as oil, adapted to be forced by the fluid pressure through a port *j'* into cylinder *j* for the raising of 85 secondary piston *k*. The conductors *o* and *p* have fluid-flow check devices *o'* and *p'* which normally close them against passage of the fluid but which on movement of their movable members *o''* or *p''* permit such 90 passage; they are here a well known type of valve whose movable member or valve 95 100 105 110

proper o'' p'' is spring-held in closed position. When conductor o is opened the fluid flowing therethrough enters cylinder a , raises the piston c and exhausts at a' , so that the piston falls, these operations being repeated so long as the fluid flow is allowed to continue and effecting reciprocation of the piston and all that it carries and a consequent "bumping" of the sand in the flask. 5

10 When conductor p is opened the fluid pressure becomes effective to raise piston k and consequently the frame m to lift or strip the flask and contained sand from the pattern A resting on platen f .

15 At present the control of the conductors is manual and entirely within the will of the attendant. Generally, therefore, the mold material is "bumped" too much or too little, time is wasted between the stopping of the 20 bumping operation and the starting of the stripping operation, and too much time is allowed in removing the mold from the raised frame m , returning said frame, placing a fresh flask thereon and filling the 25 flask preparatory to another bumping operation. We therefore take the matter of control of the conductors out of the hands of the workmen, as follows:

In a suitable support we provide a 30 constantly going master means to control both the devices o' p' . In the illustrated example, which shows a quite simple and effective form of such means, it consists of a rotary shaft q having fixed thereon cams r s whose cam-peripheries are adapted respectively to wipe against the ends of and so move the movable members o'' and p'' of 35 said devices o' and p' to the positions for opening the conductors o , p , t being an electric motor for driving said shaft and u transmission gearing connecting said shaft with the motor shaft and adapted to step-down the speed of the latter. The support is shown as a base v having brackets x to 40 support shaft q and the transmission gearing; this support may also carry the motor and it is preferred also that it carry the devices o' p' not only to make a self-contained system of all the parts concerned in the 45 control but to insure their reliable coaction. In order to adjust the speed of shaft q the bearing afforded therefor by one of the brackets x is split, as shown in Fig. 5, and the split part provided with bolt y having a thumb-nut z so that the bearing can be clamped with more or less pressure upon the shaft and thus afford a variable brake-resistance. 50 2 is a cover for protecting shaft q and other parts concerned in the automatic control of the fluid flow from being tampered with and from the dust and dirt of the foundry.

It will be understood that, as shown, the cams are removable from shaft q and so that others may be substituted therefor.

With a molding machine provided with 65 our control means the movements of the fluid actuated parts, as in "bumping" and stripping in the machine illustrated and described by way of example, are timed to occur at definite intervals of time, so that for 70 the reasons explained and apparent to those skilled in the art the product will not only be improved but a great increase in production will ensue because the attendant will be required to adapt his manual work in serving the machine to the movements of the 75 machine.

The devices o' and p' , which are arranged in the support v directly under the cams of the rotary master member, are held rigidly therein but so as to be adjustable toward and from the master member by having screwed on their threaded portions 3 $3'$ the 80 clamping nuts 4 $4'$.

Having thus fully described our invention, what we claim as new and desire to 85 secure by Letters Patent is:—

1. In combination, with the fluid actuated moving element of a mold making machine, a fluid source and means to transmit fluid from said source and cause it to actuate said element including a fluid conductor, means to alternately check and release the flow through said conductor including a 90 constantly going master member.

2. A controlling means for substantially the purpose set forth including, in combination, a support, a constantly driven rotary master member journaled in the support, and a controlling device mounted in the 100 support and having a movable control member held in position to be actuated by the master member.

3. A controlling means for substantially the purpose set forth including, in combination, a support, a constantly driven rotary master member journaled in the support, and a controlling device having a movable control member held in position to be actuated by the master member and adjustable 105 in the support toward and from the master member.

4. A controlling means for substantially the purpose set forth including, in combination, a support having a base, a constantly 115 driven master member movable in the support above the base, a controlling device extending through the base and shiftable therein toward and from said member and having a movable control member held in position to be actuated by the master member, and nuts screwed on said device and clamping the same shiftably to the base.

In testimony whereof we affix our signatures.

CHAS. G. SHAFFER.
GEORGE TREFS.
